UNITED STATES PATENT OFFICE.

FRANKLIN GATFIELD HOBART, OF BELOIT, WISCONSIN, ASSIGNOR TO FAIRBANKS, MORSE & COMPANY, OF CHICAGO, ILLINOIS, A CORPORATION OF ILLINOIS.

CRUDE-OIL VAPORIZER.

SPECIFICATION forming part of Letters Patent No. 735,376, dated August 4, 1903.

Application filed March 1, 1901. Serial No. 49,397. (No model.)

To all whom it may concern:

Be it known that I, FRANKLIN GATFIELD HOBART, a citizen of the United States, residing at Beloit, in the county of Rock and State of Wisconsin, have invented certain new and useful Improvements in Crude-Oil Vaporizers, of which the following, taken in connection with the accompanying drawings, is a specification.

10 My invention has for its object the provision of a device of the kind specified which while easy and cheap to construct will be more efficient in its action than other devices of like kind heretofore in use with which I 15 am familiar.

20 A further object of my invention is the provision of means whereby the exhaust heat of a hydrocarbon-engine may be employed in heating a casing placed within a vaporizing-chamber, the whole being provided with novel means whereby the precise amount of the exhaust heat utilized in the vaporization of the crude oil may be controlled with great nicety or, if desired, absolutely cut off.

25 Another object of my invention is the provision of a chamber through which the heated products of combustion pass, which although formed with a double passage or duct through the same can be readily constructed in a single piece or casing without any joints within said heating-chamber through which the contents might escape or come in contact with the crude oil or vapors generated therefrom.

30 Another object of my invention is the combination, with a generating device like that just described, of improved means for introducing the crude oil or hydrocarbon fluid thereto and means whereby the oil is caused to flow downward over a plurality of tabular surfaces arranged exterior to said heating chamber or casing and increasing in size toward the bottom, the said tabular surfaces being somewhat cupped or hollowed out, so that the oil may collect and be acted upon 45 by the heat upon each of the same.

The above as well as such other objects as may hereinafter appear I attain by means of the construction which I have illustrated in preferred form in the accompanying drawings, in which—

Figure 1 is a vertical section through an apparatus embodying my invention. Fig. 2 is a view, mostly in elevation, showing the upper half of the device illustrated in Fig. 1. Fig. 3 is a detail considerably enlarged in 55 order to show the portion of the feed mechanism whereby the oil is introduced to the heating-surfaces. Fig. 4 is another detail of like kind. Fig. 5 is a horizontal section taken on the line 5 5 of Fig. 1. Fig. 6 is a horizontal section taken on the line 6 6 of Fig. 1. Fig. 7 is a sectional view of the upper part of the heat-casing, showing the controlling-valve in a different position.

Referring now more particularly to Fig. 1, 65 it will be seen that in carrying out my invention I provide, first, a heat-casing 8, provided at its upper end with a heat-inlet 9 (preferably connected with the exhaust from a hydrocarbon-engine) and with an outlet 10 70 and a downwardly-projecting extension or tube 11, provided with a dividing partition or septum 12, extending downwardly to a point somewhat above the bottom of the tubular extension, thus separating the interior 75 of the tube into a double passage, through which the heated gases pass downward upon the left side and upward upon the right side, provided the valve 13 be in the position shown in Fig. 1. The valve 13 is inserted for the purpose of regulating or controlling the amount of heat that shall pass downward through the heat tube or casing, a pin 14 serving to stop the valve at the two extremes of its movement. 15 represents any convenient handle 85 for manipulating the valve 14.

Attached to the upper flange portion 16 of the heat-casing there is an outer casing 17, serving to inclose the tubular extension 11 and leave a space between the inside wall of 90 the casing 17 and the tubular extension, within which air is admitted by means of an air-inlet 18 and from which the gas is permitted to escape through the gas-outlet 19. Around the casing 17 there is a jacket 20, between 95 which and the casing there may be inserted, if desired, some packing material, as indicated at 21. At the lower end the heat-tube 11 is somewhat contracted in size and extends through the bottom 22 of the casing 17 100

and is made tight by means of the stuffing-box 23 in the manner shown. The air-inlet tube 18 is preferably extended upward within the vaporizing-chamber 24, but might, if desired, be introduced laterally from one side at a point a slight distance above the bottom or floor 22 of the vaporizing-chamber. The heat-tube 11 is encircled throughout the greater portion of its length by a series of shelf-like projections 25, preferably of larger diameter near the bottom of the tube than at the top, and at its upper end the heat-tube is encircled by a conical funnel 26, attached to the tube by means of lugs 27 in such position that there is a small opening between the funnel 26 and the tube.

At the right side of the upper end of the device shown in Fig. 1 there is an oil-inlet chamber 28, into which the oil is introduced from the oil-feed device 29, having a controlling or feed valve 30 and the overflow-pipe 31 for maintaining a fixed level of oil in the feed-reservoir 32. The oil-inlet chamber 28, into which the oil is introduced through an upwardly-pointed elbow 33, is provided with an outlet-passage 34, through which the oil already partially heated is permitted to flow down onto the funnel 26, by which it is directed against the outside surface of the heat-tube 11, down which it flows over the tabular shelf-like projections 25, striking each in turn until it is fully vaporized or reaches the bottom of the chamber. The oil is drawn through the pipe 33 by suction.

If it be desired to cut off a portion of the heat passing through the heat-tube, the valve 13 is turned so that there will be an opening downward into the heat-tube and also upward directly into the outlet passage or pipe 10. If it be desired to cut off the heat-tube altogether, it can be done by throwing the valve 13 around to the position shown in Fig. 7, thus permitting the exhaust from the engine to escape through the outlet-pipe 10 without any of the heat passing through the heat-tube.

The operation of my invention is as follows: The valve 13 being put in the position shown in Fig. 1 and the engine running, the exhaust products of combustion from the engine passing downward and around the septum 12 and thence out through the escape-pipe 10 and the valve 30 being open, oil admitted to the feed-chamber 28 runs down upon the funnel 26 and thence drops over the shelf-like projections 25 in the direction of the bottom of the chamber, the air, which is being drawn into the vaporizing-chamber 24, meanwhile acting upon the oil, (which is being highly heated by the effect of the heated tube 11,) and thus becoming impregnated with vapor is allowed to escape through the outlet 19 in the form of gas.

The lower end of the heat-tube 11 is provided with a closing-plug 35, as shown in Fig. 2, which can be removed, if necessary, for the purpose of cleaning the lower end of the tube

and for applying heat when necessary to start the operation of the device.

Having thus described my invention, what I claim as new, and desire to secure by Letters Patent, is—

1. A generator for forming hydrocarbon gas, comprising a heat-tube, a downward extension upon said heat-tube, a vaporizing-chamber entirely surrounding said heat-tube, a septum or partition in said heat-tube, forming passages on opposite sides of said partition, and a valve located at the upper end of said heat-tube, constructed to regulate the passage of the heat downward at one side of said partition and thence to its outlet, substantially as described. 75

2. A generator for forming hydrocarbon gas, comprising a vaporizing-chamber, a self-regulating oil-supply therefor, a downwardly-extending heating-tube within and surrounded by said vaporizing-chamber, a septum or partition therein, forming passages on opposite sides of said partition and passages for the heat downward at one side of said partition, through said heating-tube, and thence to the outlet thereof, substantially as described. 85

3. A generator for hydrocarbon-engines comprising a heat-tube, means for supplying the same with heat, a vaporizing-chamber around said tube, and shelf-like projections extending into said vaporizing-chamber, said projections encircling said heat-tube and increasing in diameter toward the lower end thereof, and means at the upper end of said tube for directing the oil to be heated against the exterior surface of the tube whence it may flow downward over each of said projections in turn, substantially as described. 95 100

4. A generator for hydrocarbon-engines comprising a heat-tube, means for supplying the same with heat, a vaporizing-chamber around said tube, and shelf-like projections extending into said vaporizing-chamber, said projections encircling said heat-tube and increasing in diameter toward the lower end thereof, and a funnel attached to said heat-tube for directing the oil to be heated against the exterior surface of the tube whence it may flow downward over each of said projections in turn, substantially as described. 110 115

5. A generator for hydrocarbon-engines comprising a heat-tube, means for supplying the same with heat, a vaporizing-chamber around said tube, shelf-like projections extending into said vaporizing-chamber, said projections encircling said heat-tube and increasing in diameter toward the lower end thereof, a funnel attached to said heat-tube for directing the oil to be heated against the exterior surface of the tube whence it may flow downward over each of said projections in turn, an oil-inlet chamber, and a connecting-passage from said oil-inlet chamber to the upper side of said funnel, substantially as described. 120 125 130

6. A heat-tube for a hydrocarbon-gas gen-

erator provided with a downwardly-extending partition or septum dividing the interior into a double passage-way, a surrounding vaporizing-chamber and an extension at the lower end through the vaporizing-chamber provided with a removable plug whereby the interior of the tube may be exposed, substantially as described.

7. A heat-tube for a hydrocarbon-gas generator provided with a downwardly-extending partition or septum dividing the interior into a double passage-way, and a chamber at the lower end provided with a removable plug whereby the interior of the tube may be exposed, said tube having upon its outer surface a plurality of shelf-like projections arranged concentrically thereon and of larger

diameter at the bottom than at the top, substantially as described.

8. The combination with an inclosed vaporizing-surface, and a heating-chamber with means for regulating the heat thereof, inside of said vaporizing-surface, of an inlet for oil to said surface, a constant-level oil-supply near said heating-surface, and a regulable intake-port adapted to admit oil by the suction of the vaporized oil and connecting said tank with the vaporizing-chamber, substantially as described.
